UNITED STATES PATENT OFFICE.

THOMAS ARTHUR FEE, JR., OF VANCOUVER, BRITISH COLUMBIA, CANADA, AND
HARRY LAMB, OF CHICAGO, ILLINOIS.PROCESS OF CHILLING AND AERATING FLUIDS AND DEVICE FOR CARRYING OUT SAID
PROCESS.

Application filed December 8, 1926. Serial No. 153,342.

Our invention relates to the process of chilling and aerating a fluid, and to a device for carrying out said process.

For purposes of clearness and definiteness 5 of illustration, our invention will be described as applied to the chilling of lard whereby the same is transformed from the lard in a semi-transparent liquid form to the viscous state, as we commonly know lard. 10 However, be it expressly understood that our invention is not to be deemed limited to any such specific application, but the same is coextensive with all fluids where analogous problems and conditions obtain. One such 5 other fluid is ice-cream. Our process relates to changing a fluid to a liquid or from the liquid to a viscous state or changing a gaseous fluid to the viscous state.

In the manufacture of lard according to 20 the practice heretofore commonly obtaining, the lard, after being heated in the rendering retorts, is conducted to the lard roll which comprises a large metal roll with means on the inside to cool the same so that when 25 the lard is caused to be poured upon the exterior of the drum the lard will be cooled as the roll revolves and caused to adhere to the cooled drum, and while so adhering to the drum is caused to revolve against a knife 30 edge which presses against the roll at the point where the lard has been sufficiently cooled to assume a viscous state. The said knife edge operates as a scraper to remove the lard so that it falls into a beater or pickle 35 pan chamber where beaters whip air into the lard and at the same time tend to cause the lard to move towards the pump and this pump determines the pressure under which the lard is supplied to the packing department.

Many serious objections obtain to this arrangement. In this chilling of lard one of the important steps is its proper aeration. According to the above process it will be 45 noted that the lard enters upon the roller entirely exposed to the atmospheric air of the room. This roll is some eight feet long and about five feet in diameter, therefore, the amount of exposure is great. Also, be 50 it noted that the lard upon being passed to the beaters is subjected to having the atmospheric air beaten into it. Furthermore, it will be noted that there is in all this ordinary process no control over the introduction of

air as to amount. When the level of the 55 lard in the beater or pickle pan is reduced so that the beaters in part of their revolution are partially exposed, it results in the introduction of a relatively much greater proportion of air into the lard so that it becomes 60 very soft, in fact the lard has such a quantity of air in it that it is entirely unworkable, so far as being used in filling small containers. This results in stopping the regular operations and the lard is drawn into 65 large barrel containers provided it is not too badly aerated. If the latter is the situation, it is then necessary that it be returned to the rendering room and re-rendered.

Furthermore, in the above it will be noted 70 the unsanitary character of the process. The lard is exposed to the odors that may prevail in the atmosphere of the particular district in which the plant is located, and is exposed to flies and dust. Moreover, according to the 75 above named process it will be noted, that from the knife edge around the roller to the point of pouring on the new supply of liquid lard, the roller is exposed to the air in the atmosphere. The cold roller condenses moisture from the atmosphere and causes the moisture to collect on the face of the roll and even forms frost thereon. This hinders the adhering of the lard to the roll, and is highly objectionable in that it adds water 80 to the lard. If this does not render the lard entirely unusable, it lowers the grade so that a considerable loss is incurred.

The primary objects of our invention are to provide a process and a device for chilling 85 such a fluid as lard which will eliminate and overcome these various objections and which will provide advantages which are herein-after set forth.

A primary purpose of our invention is to 90 provide a regulated aeration of the fluid, and to do this in a closed device with air that has been washed and purified, also to remove 95 said fluid from contact with the atmosphere of the room in which the process is being 100 conducted so that the same is chilled under sanitary conditions away from exposure to odors, dust and flies in a mechanism positively closed to all such.

A further primary purpose of our invention 105 is to provide for a uniformity of pressure for the chilled fluid in the conduit conducting the same to the packing room. To

the end of putting said fluid under a uniform pressure we apply the pressure to the liquid fluid as it comes from the rendering retorts.

According to the present practice the cooling of the lard roll owing to its extreme size requires considerable time and when once cooled is not easily rendered of a higher temperature so that according to common practice the lard is rendered the day before it is to be packed, and is allowed to run to the chilling roll and obviously such lard does not require a roller cooled to the same degree that is required where the lard is run directly from the rendering retort to the chilling roll. That is, where the conditions permit the lard is allowed to cool as it is possible to economize on the refrigeration and thus the lard may be run through just so much more quickly. According to present practice no means is provided for readily adjusting the temperature of the chilling means to the temperature of the liquid lard. In plants where a large roll is used and where great capacity is required, it is common practice to pre-chill by running over a smaller roller previous to running over the large chilling roller.

A primary purpose of our invention is to provide a process of chilling and a device for carrying out the same which is readily adjustable to the required degrees of temperature on the part of the refrigerating means to the temperature of the rendered lard.

According to present practice, considerable difficulty is involved in cleaning the apparatus when its operation ceases. The practice is to draw off lard to the packing room from the pickle pan until the amount of air introduced by the beaters is so great that it cannot be packed any longer in small containers and it becomes necessary to draw the remainder off into barrels, and thereafter the operators scrape the beater blades and the pans.

Another primary purpose of our invention is to provide a process and a means for carrying out said process which will permit the lard to be conducted to the packing room in a uniform condition as to air, irrespective of how much lard there may be in the chilling part, and when it is desired to cease operations to cause whatever lard there is in the chilling or condensing retort to be conducted to the rendering retort and the entire device cleaned by increasing the air pressure of the lines leading thereto.

The above mentioned general objects of our invention together with others inherent in the same are attained by the device illustrated in the following drawings, the same being a preferred exemplary form of embodiment of our invention, throughout which drawings like reference numerals indicate like parts:

Figure 1 is a view in longitudinal cross-section of a lard cooling device embodying our invention.

Fig. 2 is a cross-sectional view on dotted line 22 of Fig. 1. 70

Fig. 3 is a cross-sectional view on dotted line 33 of Fig. 1.

Fig. 4 is a view of the beater element; and

Fig. 5 is a cross-sectional view on dotted line 55 of Fig. 1. 75

A retort 6 is supplied with a plurality of material receiving tubes 7 (which are slightly longer than the retort to allow for contraction), said tubes being mounted in the disks 8 and 9 which close the end of said retort. Inlet ports 10 are provided for the admission of a refrigerating fluid to said retort while port 11 is provided as an outlet for said refrigerating fluid. A disk 12 is provided with ports 13 which are of smaller diameter than the diameter of said tubes and register with said tubes. An apertured disk 14 is revolvably mounted on shaft 15. This apertured disk 14 is mounted in the feed chamber 16 formed between disk 14 and end housing 24. The material inlet conduit 17 communicates directly with said feed chamber, and air inlet port 18 communicates with said conduit 17. At the opposite end of the cylinder is disposed a beater chamber 19 or pickle pan 19 formed between disk 12 and end housing 25. Beater blades 20 are revolvably mounted upon shaft 21. Shaft bearings 22 serve as a means for withdrawing the material from the pickle pan, which has outlet port 23.

The mode of operation of a device embodying our invention is as follows:

A fluid such as lard in a heated freely flowing semi-transparent liquid form is introduced through pipe 17 to the feeding chamber 16. Cleansed air for aeration purposes may be introduced into the incoming lard through port 18, so that the material being operated upon in chamber 16 is subjected to pressure. Apertured disk 14 which is caused to revolve by means of shaft 15, which may be connected up by any suitable power means (not shown) serves to intermittently open and close communication from chamber 16 with tubes 7. These tubes 7 are subjected to a refrigerating fluid which may be admitted through ports 10 and withdrawn through port 11. The fluid is then caused to pass into said tubes and be cooled or chilled so that it is reduced to the viscous condition. Its movement through the tubes is provided for by the intermittent application of the pressure built up in the fluid in the feeding chamber. The entire effect of this pressure is applied to a limited number of the tubes at a time. This intermittent action provides for a slowing up of the fluid as it flows through the tubes, so that it is exposed to the chilling effect to which the 100 105 110 115 120 125 130

tubes themselves are subject, and at the same time there is provided such a concentration of the pressure by the revolving of the apertured disk 14 that there is no clogging of the tubes by the condensing fluid. If it were not for this intermittent action the fluid might be caused to pass through the tubes at such a velocity that there would not be necessary exposure to the refrigerating action of the tubes necessary for its change of state. As the fluid in a viscous state rises in the pickle pan 19 the beaters 20 operate to stir and intermix the material into a homogeneous mass, and at the same time the matter is subject to the fluid pressure developed upon the fluid by the pressure applied to the fluid in causing it to move through the inlet conduit 17, and the pressure of the air entering through port 18. The pressure thus developed causes the material to flow through outlet port 23 to the metering and filling device in the packing room.

It is manifest that the air employed for aeration purposes, as well as the fluid being operated upon, is prevented completely from coming in contact with the air of the atmosphere, so that a most sanitary device is provided for carrying out this part of the process of manufacturing lard. The excluding of the fluid from contact with the air in this manner prevents it from coming in contact with the odors of the atmosphere which it might otherwise readily absorb, and also prevents the introduction of any water which may depreciate the grade of the lard, said water being derived from the condensing of the humidity in the atmosphere, as well as prevents any possibility of any dust or insects reaching the product. Furthermore, it is manifest that the amount of air through port 18 for aeration purposes may be regulated with precision, which is very much in contrast with the present process where the beaters operate upon the fluid while completely exposed to the atmosphere, and the amount of air which is caused to intermix with the fluid depends upon the depth of the fluid in the pickle pan, this depth varying decidedly when machine is about to be shut down.

Furthermore, subjecting the fluid to a pressure previous to its being chilled and causing this pressure to be communicated through the chilled fluid to the material in the beating chamber, thereby provides for the very important result of causing the fluid to pass through the outlet port 23 under a uniform pressure. The subjecting of the material in the outlet conduit to a uniform pressure and conveying it under this pressure to the metering and filling device in the packing room is a most important advantage.

The step of treating the fluid to the washed and cleansed air under control pres-

sure provides for a uniformity of aeration and the beaters in the beating chamber further insure a homogeneous product.

Obviously the product resulting from treatment in the device embodying our invention is entirely free of the objections obtaining to the present methods indicated above which arise when the material in the pickle pan becomes smaller in amount. Furthermore, it is manifest that the device is readily cleaned by merely admitting air of any desired pressure to the feeding chamber 16.

Obviously the degree of chilling may be readily controlled by changing the temperature of the refrigerating fluid. Any such change in the temperature of the fluid would manifestly be quickly registered in the product since there is only the material in the individual tubes involved as contrasted with the large heavy metallic roll of the present practice design.

The air entering through port 18 may be pre-cooled so that there is no tendency for it to add to the heat of the incoming fluid but will operate to pre-cool the fluid.

The function of the disk 12 in providing apertures of smaller diameter than the diameter of the tubes provides for greatly increasing velocity of the material entering the tubes, and, in short, subjects the material in the tubes to a jet action or to intermittent bombardment as it were. This disk 12 may be omitted where the character of the material is such that it may be caused to pass through the tubes without provision being made for such jet action.

Obviously changes may be made in the form, dimensions and arrangement of the parts of our invention, without departing from the principle thereof, the above setting forth only a preferred form of embodiment.

We claim—

1. A device of the character described embodying a retort having therethrough a plurality of fluid receiving tubes; means whereby refrigeration may be applied to said tubes; a feeding chamber disposed at one end of said retort; and means whereby air under pressure may be admitted to said chamber whereby said fluid may be forced through said tubes.

2. A device of the character described embodying a retort and having therethrough a plurality of fluid receiving tubes; means whereby refrigeration may be applied to said tubes; means whereby air under pressure may be admitted to said tubes whereby said fluid may be forced through said tubes; a fluid beater chamber disposed at one end of said retort; and beating means in said beater chamber.

3. A device of the character described embodying a retort having therethrough a plurality of fluid receiving tubes; means where-

- by refrigeration may be applied to said tubes; means whereby air under pressure may be admitted to said tubes whereby said fluid may be forced through said tubes; a 5 feeding chamber disposed at one end of said retort; and a disk disposed across the end of said retort, said disk having apertures smaller than the diameter of said tubes, said apertures registering with said tubes.
- 10 4. A device of the character described embodying a retort having therethrough a plurality of fluid receiving tubes; means whereby refrigeration may be applied to said tubes; means whereby air under pressure may be admitted to said tubes whereby said fluid may be forced through said tubes; a 15 fluid beater chamber disposed at one end of said retort; beating means in said beater chamber; and a disk disposed across the end of said retort having apertures of smaller diameter than the diameter of said tubes, said apertures registering with said tubes.
- 15 5. A device of the character described embodying a retort having therethrough a plurality of fluid receiving tubes; means whereby refrigeration may be applied to said tubes; means whereby air under pressure may be admitted to said tubes whereby said fluid may be forced through said tubes; a 20 fluid beater chamber disposed at one end of said retort; beating means in said beater chamber; and a disk disposed across the end of said retort having apertures of smaller diameter than the diameter of said tubes, said apertures registering with said tubes.
- 25 6. A device of the character described embodying a retort having therethrough a plurality of fluid receiving tubes; means whereby refrigeration may be applied to said tubes; means whereby air under pressure may be admitted to said tubes whereby said fluid may be forced through said tubes; a 30 fluid feeding chamber adjacent one end of said retort; a disk disposed across the end of said retort having apertures of smaller diameter than the diameter of said tubes, said apertures registering with said tubes; and
- 35 means revolvably disposed in front of said apertured disk whereby communication between said feeding chamber and said tubes may be intermittently opened and closed.
- 40 6. A device of the character described embodying a retort having therethrough a plu-
- rality of fluid receiving tubes; means whereby refrigeration may be applied to said tubes; means whereby air under pressure may be admitted to said tubes whereby said fluid may be forced through said tubes; a 45 fluid beater chamber disposed at one end of said retort; beating means in said beater chamber; a disk disposed across the end of said retort having apertures of smaller diameter than the diameter of said tubes, said apertures registering with said tubes; and a butterfly disk revolvably disposed in front of said apertured disk whereby communication between said feeding chamber and said tubes may be intermittently opened and 50 closed.
7. The process of chilling and aerating a fluid comprising the steps of introducing air under pressure to the fluid chilling, and beating said fluid whereby the amount of air introduced into the fluid is directly controlled and the fluid and the air admitted is prevented from being exposed to the atmosphere.
8. The process of chilling and aerating a 55 fluid comprising the steps of introducing air under pressure to the fluid, intermittently subjecting said fluid pressure in refrigerating tubes whereby said fluid is forced therethrough; chilling, and beating said fluid 60 whereby the amount of air introduced into the fluid is directly controlled and the fluid and the air admitted is prevented from being exposed to the atmosphere.
- In witness whereof we hereunto subscribe 65 our names this 13th day of November, A. D. 1926.

THOMAS ARTHUR FEE, JR.
HARRY LAMB.
